UNITED STATES PATENT OFFICE.

EMMA M. DUSTE, OF SALT LAKE CITY, UTAH.

ADJUSTABLE CURTAIN AND SHADE HOLDER.

Application filed March 10, 1924. Serial No. 698,232.

To all whom it may concern:

Be it known that, EMMA M. DUSTE, a citizen of the United States, residing at Salt Lake City, in the county of Salt Lake and 5 State of Utah, have invented certain new and useful Improvements in Adjustable Curtain and Shade Holders, of which the following is a specification.

My invention relates to holders or 10 brackets for window curtains and shades and the main object of the invention is to so construct the brackets that they may be adjusted in accordance with the length of the shade-roller after they have been erected 15 on the window casing. This has the advantage that no resetting is required after the brackets have been secured in position.

In ordinary brackets of this class, on the other hand, it is necessary to try over and 20 over again for suitable positions for the brackets to take a certain length of shade-roller. The brackets, forming the subject matter of the present invention, may be secured at the proper height on each side of 25 the window casing no matter what the length of the shade roller may be. The latter may thereupon be positioned by sliding the bearing portions of the brackets until the right distance between these bearing 30 portions has been found to properly accommodate the shade-roller. As this adjustment is possible on the right as well as on the left bracket, it is evident that the shade-roller may be symmetrically adjusted with 35 regard to the window casing.

In the accompanying drawing, one embodiment of the invention has been illustrated, and

Figure 1 is a fragmentary front elevation 40 of the curtain and shade-roller brackets in position on the window casing;

Figure 2 is a side elevation in a larger scale of one of the brackets, and

Figure 3 is a horizontal section along line 45 3—3 of Fig. 1.

In the drawing, 10 represents a window casing to which the holders or brackets are secured.

The holders or brackets which are made in 50 pairs, viz, a left hand bracket 11 and a right hand bracket 12, each consists of a body portion 13 adapted to engage the side face of the window casing and be secured thereto by means of screws or nails 14 as best seen in Fig. 2. The bracket is made from thin sheet metal and from the flat body por-

tion 13 extends forwardly an upper arm 15 provided with one or more apertures 16 adapted to receive the end of the curtain-pole. At the lower end of the body portion 60 and integral therewith is formed a pair of guide rails 17 spaced from each other and running inwardly from the body portion 13 and terminating with a bridge strap 18 connecting the inner ends of the two arms. 65 This bridge strap is secured on the window casing by means of still another screw or nail 19 as best seen in Fig. 3. The guide rails 17 are spaced a certain distance from the front face of the casing but the bridge 70 strap 18 is offset with regard to the guide rails 17 in order to contact with the front surface of the casing.

Between the guide rails 17 a portion of the plate is bent outwardly parallel to the body portion 13 to form a bearing 20 for an adjusting screw 21. This bearing portion may be formed from the part of the plate which is partially cut out to form the space 22 between the guide rails 17 and is accordingly of the same height as the width of the space 22. On the outer side of the adjusting screw 21 is shown a wing-nut 22 by means of which the adjusting screw 21 can be made to slide in and out in the bearing arm 20. 80 On the inner side of the latter and engaging the adjusting screw 21 may be provided a lock-nut 24 for securing the screw in position after adjustment. Reference numeral 25 represents the adjustable shade-roller 90 bearing which accordingly is provided with an aperture 26 near its outer end for receiving one of the pivots of the shade-roller. Ordinarily the pivot at one end of the shade-roller has to turn freely in its bracket. This 95 aperture in one of the brackets is circular while the corresponding aperture in the other bracket is oblong to receive the stationary pivot at the other end of the roller. Generally this oblong aperture for the stationary pivot is a U-shaped slot in one of the brackets opening at the upper edge thereof in order to permit the dropping in of the stationary pivot. This is a disadvantage because it often happens with a 100 hard pull on the shade that the pivot jumps out of the slot and the shade falls.

The shade-roller bearing 25 has a foot 27 at its inner end which engages the inner sides of the guide rails 17 and the ends 28 110 of the foot are bent together to embrace the corresponding guide rails 17 as best seen

in Figs. 1 and 3. The foot 27 is of sufficient length to prevent the bearing 25 from rocking on the guide rails and to permit easy sliding in a horizontal direction thereof.

5 To the bearing 25 is rigidly secured one end of the adjusting screw 21 which for this reason is provided with a head and a nut 30 for drawing it up tightly in the shade-roller bearing 25.

10 After the holders or brackets 11 and 12 have been secured as already described by means of screws or nails 14 and 19 on the right and left hand sides of the window casing as indicated in Fig. 1 and the curtain-pole mounted in the apertures in the upper arms 15, the bearings 25 are slid apart by means of their adjusting screws 21 to permit the insertion of the shade-roller between them. The distance between the two bearings 25 will then be slightly greater than the overall length measured from tip to tip of the shade-roller pivots. By means of the adjusting screws 21 and wing-nuts 23, the bearings 25 are now made to slide towards 25 each other until they engage respectively the corresponding pivots on the shade-roller. It will now be evident that the bearings 25 can be made to come much closer to each end of the shade-roller than usual, thereby 30 giving a better support for the latter. It will also be evident that a very close adjustment of the bearings 25 will be possible so that the shade 31 may hang perfectly symmetrical with relation to the window opening. As soon as the correct position of the

bearings 25 has been found, the adjusting screws 21 are secured in the bearing arms 20 by means of the lock-nut 24. The shade-roller bearings 25 will in this manner be held firmly upon the guide rails 17 and at 40 a proper distance from each other to permit an easy operation of the shade 31.

Having thus described the invention what is claimed as new is:

A curtain and shade bracket comprising 45 a body member adapted to be secured to the edge of a window casing, guide rails extending from the front edge of said body member parallel to the front face of the window casing, a bridge 50 piece connecting the inner ends of the rails and adapted to be secured to the front face of the window casing, said bridge piece being inset relative to the rails whereby the rails will be disposed in spaced relation to the window casing, a bearing arm projecting forwardly from the body member between the outer ends of the rails, a shade roller-supporting bracket having its inner end disposed between the guide rails and having a 55 foot extending upwardly and downwardly therefrom and slidably engaging said guide rails, an adjustable screw permanently secured in said bracket and extending through the bearing arm, and nuts on the screw at 60 opposite sides of said arm to lock the screw thereto.

In testimony whereof I affix my signature.

EMMA M. DUSTE. [L. s.]
